DESIGN FOR AN ELECTRIC RANGE

William J. Russell, Mansfield, Ohio, assignor to Westinghouse Electric & Manufacturing Company, a corporation of Pennsylvania

Application December 21, 1939, Serial No. 89,078

Term of patent 7 years

To all whom it may concern:

Be it known that I, William J. Russell, a citizen of the United States, residing at Mansfield, in the county of Richland and State of Ohio, have invented a new, original, and ornamental Design for an Electric Range, of which the following is a specification, reference being had to the accompanying drawing, forming part thereof, in which:

ing my new design, the concealed end of the range being like the end illustrated and

Fig. 2 is a view in end elevation of the electric range.

The characteristic features of my design reside in the backsplasher having the accessory units thereon, as shown.

I claim:

The ornamental design for an electric range, substantially as shown and described.

WILLIAM J. RUSSELL.
